UNITED STATES PATENT OFFICE.

JAMES P. BECKER, OF MIAMI, FLORIDA, ASSIGNOR TO BECKER HARDWARE MANUFACTURING CO., OF MIAMI, FLORIDA, A CORPORATION OF FLORIDA.

CLOSURE OPERATOR.

Application filed October 5, 1925. Serial No. 60,574.

My invention relates to closure operators and has particular reference to improvements in devices of the general type disclosed in my Patent 1,557,549, October 20, 1925, and in my application, Serial Number 1,282; that is, to devices in which a notched bar cooperates with a pin or stop to hold a swinging closure in different open positions as determined by the location of the notches in said bar, my purpose being to provide a simple, inexpensive, easily manipulated means whereby the location of an effective notch or notches in a bar of given dimensions may be changed to adapt that bar for use in connection with closures and closure frames of different sizes and dimensions and to permit the predetermined open positions of the closure, as determined by the location of the notches in the bar, to be varied.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:

Fig. 1 is a horizontal section through a window equipped with a closure operator of the notched bar type which in turn is equipped with the means embodying my present invention;

Fig. 2, a view similar to Fig. 1 showing the means embodying my present invention positioned to adapt the operator of Fig. 1 to a window different in certain essential respects from the window shown in Fig. 1; and

Fig. 3, a detail perspective of the means embodying my present invention.

While my invention is applicable to any closure operator embodying a notched bar cooperating with a pin or stop to hold a closure in different open positions, I have, for convenience, shown it applied to an operator of the type disclosed in my prior Patent 1,557,549 October 20, 1925, and application, Ser. No. 1,282, for holding a casement window in different positions of open adjustment, the window frame being designated at 10, the sill at 11, and the sash at 12, the latter being hinged to the frame as at 13 for outward swinging movement.

The operator herein shown is the same as the operator shown in my application 1,282 and therefore it is not necessary to again describe the same in detail, it being sufficient for the purpose of obtaining a clear understanding of my present invention merely to state that a pin 14 is secured to the sill 11 and that a bar 15 is pivoted to the sash 12 and provided in one edge thereof with notches adapted for selective engagement with pin 14 to hold the sash in different open positions, any suitable means being provided to hold the bar with a selected notch thereof in engagement with the pin whereby accidental movement of the sash from a selected position of open adjustment is prevented.

For different reasons it may be necessary or desirable to locate the pin 14 a greater or less distance from the inner face of sash 12 when the latter is closed; for example, because of the sill 11 being wide or narrow in different instances, or because of the window screens, indicated by dotted lines at 16, with which it is desirable that the plate or casing carrying pin 14 be aligned, being disposed in different instances different distances from the sash, it being desirable that the plate or casing carrying pin 14 be disposed in alignment with the screen which desirably is notched to receive said plate or casing whereby openings through which insects might pass and which otherwise would have to be provided in the screen frame to admit rod 15 may be avoided.

It is impractical to manufacture a special rod 15 for each different window or for windows in which the screens are located different distances from the sash when the latter is closed and it also is impractical to change the position of screens already in windows to cause them to align with the pin carrying plate or casing of a window operator it is desired to install. Thus, the important problem solved by my present invention is to provide means whereby a rod 15 of given dimensions may be adapted for use upon windows the sills of which are of different widths and the screens of which are located different distances from the window sash when the latter is closed.

I accomplish my purpose by forming an elongated recess 17 in bar 15 and providing a filler for said recess in the form of a block 18 having formed in opposite faces thereof, at different distances from its ends, notches

19 and 20, respectively, either of which may be made the pin engaging notch simply by turning one side or the other of the block 18 outward with respect to bar 15 when engaging said block in recess 17.

Openings are formed through block 18 for the reception of screws or other suitable fasteners 21 for securing said block to bar 15 and both notched sides of the block are counter-sunk adjacent to said openings whereby the screws or other fasteners will lie flush with the outer face of the block irrespective of which notched side of the same is disposed outwardly.

Not only may block 18 be turned to dispose either notched side thereof outward to vary the distance between the effective notch and the inner face of the sash, but it may also be turned end for end within the recess 17 to further vary the relative spacing of the effective notch with respect to the inner face of the sash, the result being that within certain limits, as determined by the length of block 18 and the relative spacing of the notches 19 and 20 therein, the location of the effective pin engaging notch may be varied to permit the pin 14 to be properly affixed to the sill 11, irrespective of the relative spacing of the sash and screen and irrespective of whether the sill be narrow or wide in a particular instance.

When block 18 is secured within recess 17 it forms to all intents and purposes an integral part of rod 15 and besides providing a means of so locating an effective notch of bar 15 to permit pin 14 to be affixed to the sill 11 at different distances from sash 12 as circumstances may demand in particular cases, said block provides a means whereby the open positions of the sash, as determined by the location of the notches in bar 15, may be varied; that is, by means of a plurality of blocks 18 located at different points along bar 15 it is possible, by manipulating said

blocks in the manner of block 18 to vary the location of the effective notches in the bar 15 longitudinally with respect to the latter whereby the sash 12 may be held open at a greater or lesser angle as may be desired.

From the foregoing description considered in connection with the accompanying drawings it is believed that the construction, operation and advantages of my invention will be clearly understood. It is desired to point out, however, that the arrangement shown may be modified within the spirit and scope of my invention as defined in the appended claims.

I claim:—

1. In a closure operator, a bar adapted to be secured to a closure, a member having a pin receiving notch therein located at different distances from the ends of the member, said member being reversible end for end to alter the position of the notch with respect to the bar, and means for securing said member in either position to said bar.

2. In a closure operator, a bar adapted to be secured to a closure, a member having pin engaging notches in different faces thereof located, respectively, different distances from the ends of the member, and means for securing said member to said bar with either notched face thereof disposed outwardly with respect to the bar.

3. In a closure operator, a recessed bar adapted to be secured to a closure, and a member having pin engaging notches in different faces thereof located, respectively, different distances from the ends of the member, said member being adapted to be secured within said recess with either notched face thereof disposed outwardly with respect to the bar and being reversible, end for end, within said recess.

In testimony whereof I hereunto affix my signature.

JAMES P. BECKER.
